Inventor

Virgil W. Blanchard

UNITED STATES PATENT OFFICE.

VIRGIL W. BLANCHARD, OF NEW YORK, N. Y., ASSIGNOR TO JOSEPH A. DAVIS, OF SAME PLACE.

FURNACE.

SPECIFICATION forming part of Letters Patent No. 413,922, dated October 29, 1889.

Application filed April 13, 1889. Serial No. 307,157. (No model.)

To all whom it may concern:

Be it known that I, VIRGIL W. BLANCHARD, of New York, in the county of New York and State of New York, have invented certain new and useful Improvements in Furnaces; and I do hereby declare that the following is a full, clear, and exact description thereof, reference being had to the accompanying drawings, and to the letters of reference marked thereon, which form part of this specification, in which—

Figure 1 is an elevation of a furnace, partly in section, showing my improved automatic pulverized-fuel feeder applied to it. Fig. 2 is a vertical section of the feeder.

The object of this invention is to supply pulverized fuel in desired quantities to furnaces, and to regulate the supply according to the intensity of heat in the furnace and the pressure of steam in a boiler used in connection therewith; and it consists in certain novel means whereby the above object can be accomplished automatically and the steam in the boiler maintained at any desired pressure, as will be fully understood from the following description, when taken in connection with the annexed drawings.

A designates a furnace, the outlet from which should communicate with a steam-boiler casing in any suitable manner.

B designates the ash-pit of this furnace; C, the grate, and D the fuel-chamber, access to which may be had by means of a door E', that should be hermetically closed during the operation of the furnace.

E designates a feeder for finely-pulverized fuel, with which feeder communicates a pipe F, leading to a suitable air-forcing engine and provided with a regulating-cock f. The

feeder E consists of a cylinder H, in which is applied a rotary worm or screw conveyer J, applied on a shaft which has a stepped cone-pulley K, keyed on one end, hereinafter again referred to. Into the cylinder H finely-pulverized fuel is fed from a hopper G, provided with a regulating-cock g', applied to the neck

g of this hopper. At the lower end of the neck of the hopper, or point of discharge thereof, commences one end of the worm-con-

veyer J, the opposite end thereof terminating in the cylinder H, just below the air-blast pipe F, and at the junction of a bifurcated pipe H' with the conveyer-cylinder H. The bifurcations H' extend into the ash-pit B, and lie on the floor thereof, as shown in Fig. 1. The said bifurcations are numerous and perforated, as indicated at a a, and these perforations are all directed toward a passage h, which forms a communication between the ash-pit and the lump-fuel chamber D outside of the margin of the grate C.

i is a removable block provided with a regulating-slide and supported on the grate at the upper terminus of the passage h. By removing this block i the coal on the grate can be raked with a suitable instrument, and by means of the slide which is applied to this block the size of the discharge-throat of the passage h can be regulated.

When the coal on the grate C is heated to a state of incandescence and the air-forcing engine and also the conveyer-worm are set in motion, the cock g' of the hopper G is more or less opened, and pulverized fuel allowed to flow into the cylinder H. The worm J will now feed the fine fuel beneath the blast-pipe F, where it is subjected to a strong blast of air, which forcibly injects this fuel through the perforated bifurcated pipe H' into the ash-pit, and from thence through the passage h into the fuel-chamber D, either over or through the body of incandescent fuel on the grate C.

The foregoing parts of the apparatus are substantially shown and described in my application, Serial No. 306,972, filed April 12, 1889, for furnaces, and are not herein broadly claimed.

In the passage of the strong currents of air mixed with the pulverized fuel through the ash-pit on their way to the fuel-chamber they will carry with them the ashes which fall through the grate and deposit them among the incandescent lumps of fuel, where they will be consumed.

K' designates a stepped cone-pulley, which is a duplicate of the pulley K on the shaft of the worm-conveyer J, and which receives the

belt *b*. The pulley *K'* is keyed on a shaft *t*, which is journaled in pillow-blocks mounted on a frame *L*, and which has also clutched on it a belt-drum *N*, that receives rotation from 5 a belt-wheel driven by an engine. (Not shown in the drawings.) This engine receives steam from the boiler, which is heated by the furnace *A*. On one end of the shaft *t*, I apply a sliding clutch *P* of any suitable kind, 10 by adjusting which the pulley *N* can be caused to turn loosely on this shaft. The bifurcated end of a lever *p* engages with the sliding portion of the clutch *P*, and the opposite end of this lever is connected to one arm of a short 15 lever *r*, which has its fulcrum on an extension of the frame of a steam-cylinder *S*. The opposite arm of lever *r* is pivoted to the piston-rod of a solid piston working in said steam-cylinder. The outer extremity of the piston- 20 rod of piston *T* is pivoted to the short arm of a steelyard *V*, on which is applied an adjustable weight *W*.

The steam-cylinder *S* receives its steam by 25 means of a pipe *c* from the same boiler which is heated by the furnace *A*, and which drives the engine that supplies the air-blast to the pulverized fuel-feeder.

The operation of my apparatus is as follows: 30 The belt *b* is adjusted on the cone-pulleys to transmit the desired speed to the conveyer-shaft, and valves *f g'* are opened, pulverized fuel being supplied to the hopper *G*. The lever *V* is then loaded according to a predetermined pressure of steam in the boiler. 35 Now, it will be observed that pulverized fuel will be fed into the furnace in regulated and desired quantities as long as the given pressure of steam in the boiler is maintained. Should, however, this pressure be increased, 40 the piston *T* will be forced outward and the long arm of the loaded lever *V* will be caused to rise, thereby disengaging the clutch *P* from the belt-drum *N* and stopping the motion of the pulverized-fuel conveyer and the 45 feed. This operation will have the effect of reducing the heat of the furnace and allowing the steam-pressure in the boiler to fall to the desired point. At the moment this takes place the weight *W* will press back the piston *T* and cause the clutch *P* to engage belt-wheel *N* with its shaft *t* again and start the 50 fuel-feeder. It will thus be observed that the pulverized fuel will be automatically fed into the furnace, and that the operation of this 55 feeder depends on the heat of the furnace and pressure of steam in the boiler heated by it.

The pulverized fuel will be supplied to the furnace faster or slower, according to the position of the belt *b* on the cone-pulleys, 60 and the fuel-conveyer will be stopped or started according to the pressure of steam in the boiler and the amount of the weight acting to hold back the piston *T* in cylinder *S*.

Having described my invention, what I 65 claim as new, and desire to secure by Letters Patent, is—

1. The combination, with the pulverized-fuel feeder and the blast-pipe, of the cone-pulleys, their belt, the belt-pulley, the clutch, and means for automatically actuating this 70 clutch and starting or stopping the feed at certain determined pressures of steam, substantially as described.

2. The combination, with a furnace and a pulverized-fuel feeder, substantially as described, of the shafting and clutch connecting with said feeder, and the means for automatically operating this clutch to start or stop the feed at a certain predetermined pressure of steam, all as and for the purpose specified. 75 8c

3. The combination of a furnace and a fuel-feeder therefor with the shaft driven by an engine and operating said feeder, the clutch engaging said shaft, and the devices, substantially as described, for automatically actuating said clutch to start or stop the feeder, 85 all substantially as specified.

4. The combination of the fuel-feeder, substantially as described, the blast-pipe connecting therewith, the steam-cylinder, its weight-controlled piston, and the connections between the same and the fuel-feeder, whereby the latter is automatically stopped or started at a certain boiler or steam pressure, substantially as and for the purpose described. 90 95

5. In combination with a furnace, an automatic pulverized-fuel feeder, an air-blast, pulleys and belts for actuating the feeder, a clutching device, a steam-cylinder communicating with a boiler and provided with a piston loaded as described, and the connections between the piston-rod and said clutching device, substantially as specified. 100

6. The combination of the injecting-pipe and a conveyer-screw arranged therein, a fuel-feed hopper, the shafts and pulleys for driving said conveyer, and the automatically-operated clutch engaging one of said shafts, whereby the conveyer is stopped or started, substantially as and for the purpose set forth. 105 110

7. The combination of the injecting-pipe arranged in an ash-pit of a furnace below the grate, with a conveyer-screw applied in a cylinder outside of the furnace, a fuel-feed hopper, a blast-pipe communicating with said cylinder, and regulating-valves applied to the neck of the hopper and to the said blast-pipe, all substantially as and for the purpose described. 115

8. The combination, with a furnace, an automatic pulverized-fuel feeder, cone-pulleys and belts for operating said feeder, and the feed-hopper and its valved neck, of the steam-cylinder, its piston, the weighted lever connected thereto, and the clutch on one of the cone-shafts, and the connections between said clutch and the piston, all constructed and arranged substantially as set forth. 120 125

9. The combination, with a furnace having an injecting-pipe below its grate, a casing connecting therewith, having a feed-hopper and a rotary screw-conveyer in said casing, 130

the cone-pulleys and belts, and the clutching device, of the air-blast pipe valved as described and communicating with said casing, the steam-cylinder, its weighted lever and piston, and the connections between the piston and clutch, all constructed and arranged to operate for the purpose and in the manner specified.

In testimony that I claim the foregoing as my own I affix my signature in presence of 10 two witnesses.
